UNITED STATES PATENT OFFICE.

JOHN JAMES McLAUGHLIN, OF BOMBAY, INDIA.

LIFE-RAFT.

1,246,129.

Specification of Letters Patent. Patented Nov. 13, 1917.

Application filed May 26, 1916. Serial No. 100,096.

To all whom it may concern:

Be it known that I, JOHN JAMES McLAUGHLIN, a subject of the Emperor of India, residing in Bombay, India, have invented certain new and useful Improvements in Life-Rafts, of which the following is a specification.

This invention relates to rafts for the saving of life at sea on the occasion of shipwreck or other mishap.

The invention consists in providing a life raft which is reversible so that in whatever manner it may be launched it will right itself and float with one of its floors available for occupants. It contains one or more air tanks set between two floors suitably framed, and fitted all around with pendent life lines. Smaller tanks are also provided between the floors to hold water and provisions. Around each floor are fitted handrails which are folded down on the floor when not in use.

A raft according to the invention is represented by way of example in the annexed drawing in Figures I, II and III, of which the respective parts are indicated by progressive numbers that are common to the three figures.

Fig. I is the raft in plan, floored with battens on suitable framing. Beneath this floor three air tanks 1 are indicated in dotted lines, and two smaller tanks 2, 3, for provisions and water. The watertight lids 18 of these tanks are also shown and the mallets 13 for closing or opening the lids. Paddles 14 are also shown for propelling the raft in case of need and rope painter 15 whereby it may be towed.

Fig. II shows the above raft as seen from the end of the air tanks 1. The floors of battens 19 cover the upper and under surface and also the sides. The provision tanks 2, 3 and dipper 12 or narrow vessel used for dipping into a small necked vessel to obtain water or other liquid are also indicated. The life lines are shown hanging over a rib 10. A steering oar 16 attached by gromet 17 is also shown.

Copies of this patent may be obtained for five cents each, by addressing the "Commissioner of Patents, Washington, D. C."

Fig. III is a side view showing the air tanks 1 longitudinally, the life lines 8, the grips 9 and on the upper side the handrail 4 erected. 11 is a sling for hoisting or launching the raft. The handrail is shown beneath, folded, and also in dotted lines extending with its braces 5. When on deck with its handrail folded this raft offers no obstruction to immediate launching. When in the water it is accessible on all sides and access is facilitated by the life lines which can be seized by the hands while the projecting edge of the submerged floor and side battens afford good footing for persons to get on board.

What I claim as my invention and desire to secure by Letters Patent is:—

1. A reversible life raft comprising in combination, a plurality of straight hollow cylindrical tanks arranged in any direction, floors composed of battens covering completely the upper and under surfaces of the tanks, water and provision tanks opening on either the upper or the under floor and a folding handrail affixed around the outer edge of the raft on the top and bottom thereof.

2. A reversible life raft comprising in combination, a plurality of straight hollow cylindrical tanks, floors composed of battens covering completely the upper and under surfaces of the tanks and also covering the sides, water and provision compartments opening on either the upper or the under floor, a folding hand rail affixed around the outer edge of the raft on both floors and a double row of life lines around each side of the raft.

In testimony whereof I have signed my name to this specification in the presence of two subscribing witnesses.

JOHN JAMES McLAUGHLIN.
